* cited by examiner

Primary Examiner—Charles A. Rademaker*Assistant Examiner*—Carla Jobe Wright(74) *Attorney, Agent, or Firm*—Brij K. Agarwal; Eckert Seamans Cherin & Mellott, LLC(57) **CLAIM**

The ornamental design for a handset, as shown and described.

DESCRIPTION

FIG. 1 is a perspective view of a handset depicting our new design;

FIG. 2 is another perspective view thereof;

FIG. 3 is a left side elevational view thereof;

FIG. 4 is a front elevational view thereof;

FIG. 5 is a bottom plan view thereof;

FIG. 6 is a top plan view thereof;

FIG. 7 is a right side elevational view thereof; and,

FIG. 8 is a rear elevational view thereof.

The broken line showings of the rectangular feature on the front of the handset in FIGS. 1 and 4, the elliptical feature at the bottom right side of the handset in FIGS. 1, 4, 7, and 8, and the indented/stepped feature at the top right corner of the handset in FIGS. 1, 2, 4, 6, 7, and 8, are for illustrative purposes only and form no part of the claimed design.
